UNITED STATES PATENT OFFICE.

ABRAM A. KNOWLES, OF CANYON FERRY, MONTANA.

MOTOR SLEIGH.

Application filed October 14, 1922. Serial No. 594,449.

To all whom it may concern:

Be it known that I, ABRAM A. KNOWLES, residing at Canyon Ferry, in the county of Lewis and Clarke and State of Montana, 5 a citizen of the United States, have invented certain new and useful Improvements in Motor Sleighs; and I do hereby declare the following to be a full, clear, and exact description of the invention, such 10 as will enable others skilled in the art to which it pertains to make and use the same.

My invention relates to improvements in motor sleighs, and more particularly to propelling means for sleighs.

The object of the invention is to provide propelling means coacting with the atmosphere for driving and controlling the direction of a sleigh.

20 A further object is to provide propelling means coacting with atmosphere and which moves or swings in unison with the front runners of the sleigh.

A further object is to provide propelling 25 means for a sleigh which is simple, inexpensive, and durable in construction, easy in operation, and attractive in appearance.

The invention consists in the several features, and the construction, combination, 30 and arrangement of such features as is more fully hereinafter described and claimed.

Referring to the drawings:—

Fig. 1 is a side elevation of a sleigh or sled with my invention applied.

35 Fig. 2 is a sectional view of the mounting for the propeller.

In the drawings in which similar reference characters denote similar parts throughout the several views, 1 represents the body or 40 frame of the sleigh, 2 the rear runners and 3 the front runners, 4 the steering rod having a steering wheel 5 at its upper end, and a gear 6 at its lower end which meshes or engages with a rack 7 mounted on a platform 8 comprising two blocks.

The sleigh is propelled by means of two propellers 9 and 10, preferably five feet in diameter, one mounted at the front and the other at the rear of the sleigh.

50 The front propeller 9 is mounted on a short upwardly inclined shaft 11, preferably inclined at an angle of twenty-eight degrees, and 12 is a sleeve formed on the upper end 13 of a bracket or post 14 and 55 in which sleeve the shaft 11 is mounted.

The rear propeller 10 is mounted on the

extreme end 15 of a driving shaft 16, extending lengthwise of the sleigh and supported by means of brackets 17, 18, 19, and 20 extending upward from the floor 21 of 60 the sleigh.

The front end of the driving shaft 16 is provided with a universal joint 22 which may be of any well known style, and the inner end of the shaft 11 of the front propeller 9 is operatively mounted therein.

The propelling means for the driving shaft 16 may be the usual type of automobile engine 23 with sprockets 24 and 25 on the engine shaft and driving shaft, respectively, and an endless sprocket chain 26 connecting the sprockets; or any other desired motive or driving power, and connections with the driving shaft may be used which are found suitable or desirable.

The floor 21 has an extension 27 at the front end provided with a hole 28, and 29 is a U-shaped horizontal plate on the upper part 30 of which the foot 31 of the bracket or post 14 is mounted and secured by means of bolts 32, while the lower part 33 of the plate is secured to the platform or blocks 8 by means of bolts 34, and 35 is a vertical pivot pin or bolt which pivots the U-shaped plate 29, carrying the bracket and 80 post 14 and propeller 9, to the extension 27 of the floor for the purpose of allowing 85 of the swinging or movement of the propeller 9 with the front runners 3.

A cross beam 36, to which both of the 90 front runners 3 are connected, is pivoted centrally to the blocks 8 by means of a horizontal rod or pin 37 in order to provide for the play or motion of the runners.

It will be seen that the front runners 3, 95 the blocks 8, cross-beam 36, U-shaped plate 29, the post 14 and front propeller 9 all turn together on the extension 27 of the floor 21, on the vertical pin 35 secured centrally of the blocks 8, and that in turning 100 corners the front propeller assists in turning the sleigh.

I do not wish to be understood as limiting myself to the specific details of construction and arrangement as herein described and illustrated, as it is manifest that variations and modifications may be made in the features of construction and arrangement, in the adaption of the device to various conditions of use, without departing from the spirit and scope of my invention and improvements. I therefore 110

reserve the right to all such variations and modifications as properly fall within the scope of my invention and the terms of the following claim.

5. What I claim is:—

In a motor sleigh, a cross beam, runners secured thereto, a platform pivoted to the cross beam adapted to allow for play between the runners and platform, an extension of the floor, a U-shaped plate secured to the platform and embracing the

floor extension, a post secured to said U-shaped plate having a propeller and a vertical pivot pin carried by the platform and extending through the U-shaped plate and the extension of the floor whereby the said parts are pivotally mounted on the said floor extension.

In testimony whereof I have affixed my signature.

ABRAM A. KNOWLES.
